OF SANFORD, MAINE, A CORPORATION OF MAINE

PILE FABRIC AND METHOD OF MAKING THE SAME

Application filed January 17, 1929. Serial No. 333,081.

This invention relates to the weaving of a warp pile fabric and especially a plush fabric of the so-called **W** weave type in which the pile warp threads are of mohair or a like slippery fiber.

5 Pile fabrics such as pluses, velvets, etc. may be divided into two classes which are commonly referred to as the **W** weave type and the **V** weave type. In the **W** weave each 10 pile loop is looped about three or more filling threads, each loop passing from the pile face of the fabric under one filling thread and then over one or more filling threads and then under another filling thread and back to the 15 pile face of the fabric. This gives each loop a shape somewhat like the letter **W**; hence the designation **W**-weave. In the **V** weave fabric each pile loop is looped about a single filling thread, that is, each loop passes from the pile 20 face into the body of the fabric around a single thread and then back to the pile face of the fabric again, and thus has the shape of the letter **V**; hence the designation **V**-weave.

25 In the **W** weave fabric each pile loop is securely anchored or tied into the body of the fabric because of the fact that it loops about a plurality of filling threads, while in the **V** weave fabric the pile loops are much less 30 securely anchored because each pile loop loops about a single filling thread only.

There is less expense involved in making a **V** weave pile fabric than a **W** weave pile fabric, partly due to the difference in the cost 35 of the material going to make up the fabric. In these warp pile plush fabrics the pile loops are formed from pile warp threads, which during the weaving operation, are inter-looped with the filling threads. Usually the 40 material from which the pile warp threads are made is considerably more expensive than that from which the other warp threads and filling threads are made, for example, the pile warp threads may be of mohair yarn while 45 the other warp threads and the filling may be cotton.

In the case of a **W** weave fabric where each pile loop is looped about a plurality of filling threads each loop will contain a 50 much greater length of yarn than in the

case of the **V** weave fabric where each pile loop is simply looped about a single filling thread. This extra length of the expensive pile warp threads which is involved in making the pile loops in the **W** weave pile fabric adds very materially to the cost of production.

But while less of the expensive yarn is used in the weaving of a **V** weave pile fabric yet the weaving of this fabric involves some difficulties not present in the weaving of the **W** weave fabric. Since in the **V** weave fabric each pile loop is looped about a single filling thread only, said loops are not so securely anchored in the body of the fabric as in the case of the **W** weave fabric, and in order to hold the pile loops in the **V** weave fabric it has been necessary to employ an extra warp separate from and in addition to the warp comprising the regular warp threads. This extra warp is carried on a beam which is separate from that carrying the regular warp.

The threads of the regular warp are during the weaving operation under tension while the threads of the extra warp may have little or no tension and during the weaving operation these extra warp threads become crowded into the body of the fabric and thus assist in holding the **V**-shaped pile loops in place. Various terms are used to designate this extra warp such as "slack warp," "binding warp," "extra warp," etc.

While this extra warp has been regarded as necessary in the making of a **V** weave plush in order to assist in binding the pile loops into the fabric yet there are certain disadvantages that result from its use.

One is that the presence of this extra or slack warp produces a crowding of the warp threads in the reed and harnesses of the loom. In weaving many plush fabrics it is more or less common to employ a reed having eighteen to twenty-two dents to the inch and in threading up a loom for weaving a double plush fabric of the **V** weave type there will be in each dent two pairs of regular or ground warp threads, two pairs of the warp threads of the extra or slack warp besides a pile warp thread. In other words

there will be nine threads to the dent, and with twenty-two dents to the inch this would means one hundred and ninety-eight threads to the inch.

5 The handling of this large number of warp threads complicates weaving conditions as the crowding of the threads in the dents of the reed and in the harnesses interferes with the proper formation of the sheds, especially since some of the threads in each dent are those of the extra warp which are more or less slack. Moreover, where the threads are so crowded in the loom there is more danger of broken warp threads, 10 and each broken warp thread involves the stoppage of the loom to have the damage repaired. Hence the presence of the extra slack warp threads, which has been deemed necessary in the weaving of the V weave fabrics, results in slowing down production due to more frequent stoppage of the loom for repairing broken warp threads.

Furthermore, since the threads of the extra warp are more or less slack the actual 25 tension of the individual extra warp threads will vary more or less as the weaving proceeds, thus establishing a condition which tends to produce an unevenness in the pile surface of the fabric which detracts from its 30 appearance. Hence while it has been deemed necessary to use the extra or slack warp in the production of V weave fabrics, yet the presence of this extra warp produces various disadvantages which it is highly desirable to 35 overcome.

It is one of the objects of my present invention to provide an improved method of making a V weave pile fabric by which such a fabric can be made without the use of the 40 additional or extra warp and which fabric when completed has all the desirable characteristics of a high-grade plush as well as some additional desirable characteristics.

In carrying out my invention I weave a 45 V-weave warp pile fabric with the usual number of picks per inch but with simply the pile warp and the ordinary tensioned or ground warp, the extra or slack warp which caused the above recited disadvantageous conditions 50 being eliminated. In other words the fabric is initially woven with a subnormal number of warp threads requisite to bind the pile V's into the fabric occasioned by the omission of the slack warp threads heretofore employed for that purpose. After the fabric 55 thus made from interweaving the threads of the pile warp and the regular tensioned warp with filling threads is taken from the loom I apply to the back face of said fabric a thin 60 film-like coating of pyroxylin or some other similar binding material which serves to bind together the portions of the threads exposed on the back face without, however, appreciably obscuring the texture of the fabric.

65 I find that the binding effect of this thin

film-like coating of pyroxylin is such that it ties the V-shaped pile loops into the fabric more firmly than is done by the loose or slack warp threads of the extra warp which have heretofore been used in the V weave fabric. 70 The absence of the threads of this extra warp (four threads to the dent in the weaving of a double plush fabric) greatly facilitates the weaving operation, partly because it relieves the dents of the reed and the harnesses from the crowded condition which obtains when the extra warp is used and thus eliminates the disadvantageous weaving conditions above referred to. In fact, with a reed having twenty-two dents to the inch the elimination 75 of the extra warp will remove from the reed and harnesses something over five thousand threads in a sixty inch reed space.

This diminution in the number of threads in the dents allows the threads in each dent 80 to freely pass each other during the making of the shed and it produces a condition which reduces greatly the possibility of the threads becoming fouled or tangles or broken through the presence of a knot in any thread. Moreover, since all the warp threads of the fabric, 85 that is, the pile warp threads and the regular warp threads, are under a controlled tension the result is that the pile face of the fabric 90 will present an even uniform appearance free 95 from pits or "crowfeet" or other imperfections which are apt to develop when the extra warp is used.

The weaving of the fabric in accordance 100 with my invention by omitting the slack warp threads and substituting the flexible binding material does not of itself involve any change in the number of pile V's per unit of area. In other words, a fabric embodying 105 my invention has as many pile V's per unit of area as a corresponding fabric woven with the usual slack warp threads for binding the pile V's in the fabric. If then the number of picks be the same in both types of fabric the 110 quality of the pile face will be same but the appearance of my fabric is better for the reasons above set forth.

The pyroxylin or other binding material 115 which is applied to the back face of the fabric is not only of such nature that it will not obscure the texture of the fabric but it is not affected by nor does it affect the operation of dyeing, scouring, washing or otherwise treating the fabric and, therefore, the plush fabric 120 with the pyroxylin-coated back may be dyed, scoured, or otherwise treated during the finishing operations in the same manner as a fabric without the backing. In fact, the presence of the pyroxylin coating on the back 125 of the V weave plush fabric from which the extra or "slack" warp threads are omitted is highly advantageous during the dyeing, scouring, washing or other finishing operation as it holds the fabric in shape and pre- 130

vents the pile loops from becoming loosened or pushed through the back of the fabric.

In order to give a better understanding of the invention I have illustrated in the drawings diagrammatically a V weave plush fabric embodying my invention.

Fig. 1 illustrates diagrammatically the V weave with the extra warp omitted in accordance with my present invention;

10 Fig. 2 is a perspective view illustrating more or less diagrammatically a fabric embodying my invention as it is initially woven.

Fig. 3 is a fragmentary perspective view of the completed fabric.

15 As stated above it has heretofore been customary in the weaving of V-weave warp pile fabrics to employ a set of slack or stuffer warp threads in addition to the set of ground warp threads, this set of slack warp threads being 20 for the purpose of binding the pile V's into the fabric. In weaving a double warp pile fabric having the slack or stuffer warp threads it has been customary to place in each dent of the reed two pairs of the tensioned or ground warp threads, one for each fabric, two pairs of the slack or stuffer warp threads, one pair for each fabric, and a pile warp thread which passes alternately from one fabric to the other. This makes nine 25 threads in each dent thereby producing the crowded condition of the warp threads above referred to.

In weaving a V-weave pile fabric in accordance with my invention the extra or 30 "slack" warp is omitted thereby removing from each dent four "slack" warp threads when a double pile fabric is being woven. This will leave in the fabric only the tensioned warp threads and the pile warp threads together with the filling threads, and in the case of a double pile fabric each dent will carry only the two pairs of tensioned warp threads together with one pile warp thread. This is shown in Fig. 1 which illustrates in full lines 35 the warp threads which are in each dent of the reed. This includes the tensioned or ground warp threads 2 and 3 in the upper fabric, the tensioned or ground warp threads 4 and 5 in the lower fabric, and the pile warp thread 10 which passes from one fabric to the other. This pile warp thread passes around alternate filling threads 12 in each fabric as is usual in V-weave warp pile fabrics and the adjacent warp pile threads have a staggered relation as indicated by the full and dotted line warp pile threads 10 and 11 in Fig. 1, it being understood that these represent the warp pile threads in adjacent dents. This reduction in the number of threads in each dent greatly simplifies the weaving operation and eliminates therefrom the various difficulties and complications above referred to and which have heretofore accompanied the weaving of a double pile V-weave fabric

which embodies in its construction the slack warp threads.

The omission of the extra or "slack" warp threads not only removes the crowded condition of the threads in the dents of the reed and harness which is present when the extra warp is used, but it enables production to be speeded up. In weaving the V-weave warp pile fabric having the "slack" warp threads there are three separate warps used, each 70 wound on its own beam, to wit, the pile warp, the regular tensioned warp and the extra or slack warp, each of which has to be drawn into the loom separately. When during the weaving any one of the warps runs out it 75 becomes necessary to tie in a new warp. This tying-in operation is necessarily a slow and tedious one and involves stopping the loom for approximately a day. The omission of the extra warp eliminates the necessity of drawing into the loom the five thousand or 80 more threads composing this warp and also eliminates the necessity of stopping the loom for a day or so at various intervals in order to tie in a new extra or "slack" warp. Furthermore, where the "slack" warp is omitted and there is less crowding of the warp threads in the reed and harness the danger of breakage of warp threads is much reduced so that in weaving the fabric shown in Fig. 1 the 85 stopping of the loom to piece up a broken thread is much less frequent than in weaving the V-weave warp pile fabric having the "slack" warp threads. Furthermore, where the extra or "slack" warp is omitted it is possible to divide the tensioned warp on to two beams, one of which will be located in the loom in the position usually occupied by the beam carrying the extra or "slack" warp. By 90 thus dividing the tensioned warp between two warp beams it is possible to use a warp of double the length that can be used where the entire tensioned warp is wound on a single beam and this will reduce the stoppage time required for tying in a new warp. In fact, 95 in weaving a fabric such as shown in Fig. 1 the stoppage time of the loom may be reduced as much as fifty percent over what it is in weaving a V-weave warp pile fabric having the "slack" warp threads.

100 Then again, less power is consumed in weaving the fabric shown in Fig. 1 than in weaving a V-weave warp pile fabric having the "slack" warp threads, and the loom can be run faster. The cost of production of the V weave fabric shown in Fig. 1 is thus considerably less than that of the V-weave warp pile fabric having the "slack" warp threads and some factors which contribute to this reduction in cost may be summarized as 105 follows:

110 A reduction in stoppage time of the loom required for drawing in and/or tying in the warps;

115 A reduction in the cost of the material used

since the omission of the extra warp eliminates four out of every nine warp threads heretofore used in weaving a double plush fabric or about five thousand threads in a 5 sixty inch reed space, and the cost of the pyroxylin coating is considerably less than the saving in yarn;

Faster operation of the loom;

10 Less weaving time lost in piecing up broken ends.

After the fabric has been woven as shown in Fig. 1 it is cut into the two fabrics in usual manner thereby producing the V-pile loops 14 in each fabric, and then the coating 15 15 of pyroxylin or other binding material is applied to the back face. This coating will 20 preferably be a thin film-like coating which does not appreciably obscure the texture of the back face of the fabric. It does, however, bind together the threads which are exposed on the back face and thereby acts as a 25 substitute for the omitted slack warp threads in binding the pile loops into the fabric.

The completed fabric with the pyroxylin 25 coating on the back face is one in which the pile loops are anchored in the fabric more securely if anything than could be done with the use of the extra or "slack" warp threads and since the fabric is woven without the 30 extra or "slack" warp threads and hence without the disadvantages resulting from the use of them, the pile face of the fabric has a better and more even appearance than is possible to produce where the extra warp 35 threads are used. The weaving of the fabric with the slack warp threads omitted does not involve any change in the number of picks per inch nor in the number or spacing of the pile V's. In other words the fabric 40 may be woven in accordance with this invention with the same number of pile V's per unit area as when the slack warp threads are used to bind the pile V's in the fabric.

The invention, therefore, may be considered 45 as a V-weave warp pile fabric initially woven with a subnormal number of warp threads requisite to bind the pile V's into the fabric occasioned by the omission of the slack warp threads heretofore used for this purpose, this deficiency of warp threads being 50 made good by the application of a thin film-like coating of pyroxylin to the back face of the fabric after it is woven. The fabric as shown in Fig. 1 will naturally be of lighter 55 weight as it comes from the loom than the V-weave warp pile fabric having the "slack" warp threads incorporated therein because it contains so many less warp threads but this lightness in weight is made up by the coating 60 of pyroxylin applied to the back of the fabric. The change in the weave or fabric structure of the V-weave warp pile fabric which is the result of omitting the "slack" or stuffer warp threads does not result in 65 any change in the number of the pile loops 14

per unit of area, nor in their relative arrangement and hence the pile face of the fabric embodying this invention is in no way inferior to that of a V-weave warp pile fabric in which the slack or stuffer warp threads are 70 used. In fact, the quality is improved as the omission of the "slack" warp threads eliminates the crowded condition of the warp threads in the dents and in the harnesses of the loom which frequently resulted in producing a somewhat uneven appearance in the pile surface and such elimination results in a better and more even pile surface. 75

A V-weave plush fabric may be considered as having rows of V-shaped pile loops running lengthwise of the fabric, each row comprising the loops formed from a single pile warp thread and each loop being looped about a single filling thread. In my improved fabric wherein the extra warp is 80 omitted there will be one such row of pile loops for each two warp threads in the fabric, each row of pile loops being thus separated by two warp threads only. 85

Furthermore, as stated above the pyroxylin coating is not affected by nor does it affect the finishing operations to which the fabric is subjected after it is woven, such for instance as scouring, dyeing, washing, etc. The pyroxylin has no affect upon the dye liquor 90 nor is it affected by the dye liquor and being on the back face of the fabric it does not affect in any way any of the finishing operations usually performed on the pile face of the fabric. In fact, the presence of this pyroxylin backing is an advantage during such operations as it securely ties the pile loops into the fabric, and thus prevents their becoming loosened. 95

While I have herein referred to the invention as applied to a plush fabric yet it will be 100 obvious that the principle involved in the invention is also applicable to other pile fabrics than those which are commercially known as "plush fabrics."

I claim.

1. A V-weave warp pile fabric having ground warp threads, filling threads and pile V's, each pile V being looped about a single filling thread, said fabric being initially woven with the filling threads around which the pile V's are looped in substantially the same close arrangement as in the usual V-weave warp pile fabric but with a subnormal 110 number of warp threads occasioned by the omission of the slack warp threads which are employed in said usual V-weave warp pile fabric to bind the pile-V's into the fabric, said fabric having applied to its back face a coating of flexible binding material that binds the pile V's into the fabric and thus 115 makes good the deficiency caused by the omission of the slack warp threads. 125

2. The method of making a V-weave warp pile fabric which consists in initially weaving the fabric with a subnormal number of 130

warp threads for the use to which the fabric is to be put resulting from the omission of the slack warp threads usually employed to bind the pile V's in the fabric, and in so doing looping each pile V about a single filling thread, beating up the filling threads to give them substantially the same spacing as exists in the usual V-weave warp pile fabric having the slack warp threads to bind the pile V's

5 10 15 in the fabric, and then applying to the back-face of the fabric a coating of flexible binding material that ties or binds the pile V's into the fabric and thus makes good the deficiency caused by the omission of the slack warp threads.

3. A V-weave warp pile fabric having ground warp threads, filling threads and pile V's, each pile V being looped about a single filling thread, which fabric is initially woven 20 with a subnormal number of warp threads requisite to bind the pile V's into the fabric occasioned by the omission of the slack warp threads heretofore employed for that purpose but without any reduction in the number 25 of filling threads or pile V's due to such omission, and which fabric so initially woven has applied to its back a coating of flexible binding material that binds the pile V's into the fabric and thus makes good the deficiency 30 caused by the omission of the slack warp threads.

4. The method of making a V-weave warp pile fabric which consists in initially weaving the fabric with a subnormal number of warp 25 threads requisite to bind the pile V's into the fabric occasioned by the omission of the slack warp threads heretofore employed for that purpose but without any reduction in the number of filling threads or pile V's due 40 to such omission, and then applying to the back face of the fabric a coating of flexible binding material that ties or binds the pile V's into the fabric and thus makes good the deficiency caused by the omission of the slack 45 warp threads.

In testimony whereof, I have signed my name to this specification.

WM. S. NUTTER.
